UNITED STATES PATENT OFFICE

OSCAR ZINGG, OF BADEN, SWITZERLAND, ASSIGNOR TO AKTIENGESELLSCHAFT BROWN BOVERI & CIE., OF BADEN, SWITZERLAND, A CORPORATION OF SWITZERLAND

CIRCUIT BREAKER

Application filed April 13, 1927, Serial No. 183,278, and in Germany October 8, 1926.

This invention relates to electric switch apparatus and pertains more particularly to circuit breakers for handling heavy currents. It has to do with that type of such apparatus wherein arcing contacts are employed in addition to the main contacts.

The general object of the invention is the provision of improved mechanism of the sort specified above which will open and close the main contacts and the arcing contacts in sequence, the opening and closing movements of the arcing and main contacts being effected at different speeds.

Another object is the provision of mechanism of the sort specified which is certain and positive in operation, of simple and stable construction, and not liable to structural or functional disorders.

Other and further objects of the invention will be pointed out or indicated hereinafter, or will be apparent to one skilled in the art upon an understanding of the invention or its employment in practice.

In the accompanying drawing forming a part of this specification, I show, by way of example, one form of device embodying the invention, but it is to be understood that this is not to be construed in any fashion having the effect of limiting the appended claims short of the true and most comprehensive scope of the invention in the art.

In the drawing,

Fig. 1 is a sectional elevation of an oil circuit breaker; and

Fig. 2 is a sectional elevation taken at right angles to Fig. 1, some of the operating parts being shown in section on the line 2—2 of Fig. 1.

The length of the arc formed when an electric current is interrupted depends primarily on the voltage and current density, but the speed at which the contacts move constitute another factor of particular importance in the case of oil immersed switches.

In apparatus for handling currents up to

two thousand amperes, satisfactory results may be obtained with switching speeds of from one to three meters per second, and oil switches in which the main brushes and the arcing contacts are rigidly connected can be operated at these speeds without difficulty.

With heavier apparatus, however, suitable for dealing with heavier currents, it is of advantage to operate the heavy main brushes and the lighter arcing contacts separately, so that the heavy main contacts may be operated at a slower speed and shorter travel that may be most advantageous in effecting a quick termination of the arc.

The present invention provides an effective apparatus for accomplishing this result in a positive manner without involving the employment of delicate parts such as catches, trip springs or the like. By thus operating the heavy main contacts at a considerably lower velocity than is desirable and permissible in the operation of the relatively light arcing contacts, and moving them through only a fraction of the distance, the work required for accelerating the contacts and breaking the circuit may be kept at a minimum, and the apparatus as a whole relieved of shocks and stresses attendant upon the starting and stopping of heavy masses incident to their rapid movement through substantial distances.

The nature of the invention may be most readily ascertained by reference to the example shown in the drawing. Here the reference numeral 10 designates the tank or casing of the oil switch, which houses the operating parts and retains them immersed in a body of oil. The leading-through bushings are designated 11, and carry the stationary main contact members 12 and the stationary arcing contact members 14. The operating shaft 15 enters the upper portion of the casing and is connected with a coiled spring 16 which is tensioned by rotation of the shaft in one direction, so that upon release of the shaft the spring will throw it

75

90

back in the opposite direction. The shaft carries crank arms 17 to which are connected links 18 and 19. The links 18 are connected to the upper main contact yoke 20, while the links 19 are connected to the lower main contact yoke 21, said yokes being guided on the guides 22 which depend from the cover of the casing. According to this arrangement, the main contact yokes 20 and 21 will be moved apart in a vertical direction by rotation of the shaft 15 in one direction, and will be caused to approach each other by rotation of the shaft in the other direction. The yoke 20 carries the upper main contact brushes 24, while the yoke 21 carries the lower main contact brushes 25. These brushes engage respectively the top and bottom sides of the main contacts 12 under counterbalancing pressures, so that the mountings of the main contact members do not have to support these closing pressures. These yoke members 20 and 21, of course, are of non-conductive material. The yoke 20 carries two downwardly extending rack rods 26 which mesh at opposite sides with two independently rotatable pinions 27. These pinions are journaled in a sliding frame 28 which has guiding support on said rack rods and flexible support on the lower yoke member 21 through the medium of a coiled spring 29. Attached to the sliding frame 28 and extending down through the spring 29 and through a bore in the lower yoke 21, is a stop rod 30 carrying at its lower end a coiled spring 31. Slidably mounted in the frame 28 and meshing with the pinions 27 on the sides opposite the rack rods 26, are the rack rods 32 which support at their lower ends the arcing contact yoke 34 which carries the movable arcing contacts 35 positioned for cooperation with the stationary arcing contacts 14. The rack bars 26, at their lower ends, pass through guides 36 on the yoke 21, and the rack bars 32 likewise pass through said guides and through guides 37 on the yoke 20.

In the drawing, the apparatus is shown with both the main and arcing contacts in the closed positions in which condition of the device the spring 29 is compressed. In the opening operation, rotation of the shaft 15 moves links 19 downwardly and links 18 upwardly at like speed. Links 18 move yoke 20 upwardly, while links 19 move yoke 21 downwardly, causing the main brushes 24 and 25 to be separated from contacts 12. Arcing contact yoke 34 meanwhile remains stationary, so that the arcing contacts remain closed. The upward movement of yoke 20 moves rack rods 26 upwardly so that pinions 27 are rolled upwardly on rack rods 32, carrying sliding frame 28 and stop rod 30 with them. This upward movement of stop rod 30, and the downward movement of yoke 21, brings stop spring 31 against the lower side of yoke 21, whereupon the continued

downward movement of yoke 21 moves sliding frame 28 downwardly. Thereupon, by virtue of the coupling through pinions 27, the continued upward movement of rack rods 26 and downward movement of frame 28 causes rack rods 32 to be moved downwardly, thereby separating the arcing contacts 34 and 14. This downward movement of rack rods 32 and consequently the movement of arcing contact yoke 34 and arcing contacts 35 is at a velocity three times that of the velocity of the main brushes 24 and 25. This is obtained as follows:

If s equals the velocity of the yoke 21 which carries the axle of pinions 27 downwardly, so and also the velocity of yoke 20 which carries rack rods 26 upwardly, it follows that the peripheral velocity of pinions 27 is $2s$. This would represent the velocity at which the rack rods 32 are moved downwardly if the axle of the pinions were stationary, but since the pinions have a downward movement bodily at velocity s , this must be added to the velocity of the rack rods 32, making their total velocity $3s$, or three times the velocity of the main brushes 24 and 25. Since the distance is proportional to the speed, it is evident that the arcing contacts 35 will be moved through three times the distance traversed by the main brushes 24 and 25, less the distance of relative movement between frame 28 and yoke 21. It is to be observed, therefore, that by this arrangement the main brushes may be permitted to have a much shorter travel and much slower speed than may be requisite or desirable for effecting a quick termination of the arc.

In the closing of the switch, the operations above described take place in the reverse sequence and directions. With the rack rods 32 and the frame 28 at their lower positions, the initial approaching movement of yokes 20 and 21 will elevate the rack rods 32 and the arcing contacts 35 at a velocity three times that of the brushes 24 and 25, but the arcing contacts 35 will close on the contacts 14 in advance of the closing of the brushes 24 and 25 on the contact 12, by a distance representative of the extent to which the spring 29 is compressed when all the contacts are closed, which is the distance of relative movement between frame 28 and yoke 21. From the time the arcing contacts close, the yokes 20 and 21 traverse respectively a distance equal to the distance of relative movement of frame 28 and yoke 21, and during this time, the rack rods 32 remain stationary, and the pinions 27 are rolled downwardly on rack rods 32 so that frame 28 is moved downwardly to compress the spring 29. The energy of spring 29, when it is thus compressed, is exerted through pinions 27 and rack rods 32 to hold the arcing contacts closed. To add to the closing pressure and prevent the arcing contacts being "kicked" open by a current

surge as they come into contact, it may be desirable to make them of the solenoid type, as described in the co-pending application of Gottfried Bruhlmann, Serial No. 671,583, filed October 29, 1923.

5 What I claim is:

1. In electrical switch apparatus, in combination, main contact carriers, actuating means for moving said main contact carriers in opposite directions, arcing contacts, a pinion operable to move said arcing contacts, and means operable from the main contact carriers for actuating said pinion.

10 2. In electrical switch apparatus, in combination, main contact carriers, means for moving the same in opposite directions, main contacts carried by said carriers, a pinion shiftable relatively to said carriers, arcing contacts operable by said pinion, and operable 20 connections between said pinion and said contact carriers for driving the pinion.

15 3. In electrical switch apparatus, in combination, relatively movable main contacts, actuating means for moving the same in opposite directions, arcing contacts movable relatively to the main contacts, a pinion having driving connection with one of the main contacts and a lost motion connection with the other main contact, and a driving connection 25 between said pinion and the arcing contacts.

20 4. In electrical switch apparatus, in combination, relatively movable main contact carriers, actuating means for moving the same in opposite directions, main contacts carried 35 by said carriers, arcing contacts movable relatively to said carriers, transmission mechanism carried by said carriers, and a driving connection between said transmission mechanism and said arcing contacts operable to 40 provide for actuation of the latter.

45 5. In electrical switch apparatus, in combination, relatively movable main contact carriers, main contacts carried thereby, an arcing contact carrier shiftably supported on the main contact carriers, an arcing contact 50 carried by the arcing contact carrier, means operable by the main contact carriers for shifting the arcing contact carrier relatively thereto, and means for actuating the main contact carriers.

55 6. In electrical switch apparatus, in combination, a guide member, stationary contacts, main contact carriers movable on the guide member, main contacts carried by said main contact carriers for cooperation with the stationary contacts, an arcing contact carrier supported on the main contact carriers, an arcing contact carried by said arcing contact carrier for cooperation with the stationary 60 contacts, means operable from the main contact carriers for moving the arcing contact carrier relatively thereto, and means for actuating the main contact carriers.

65 7. In switch apparatus, contacts disposed for movement toward and away from each

other into and out of contacting position, second contacts disposed for movement into and out of contacting position, and gearing comprising cooperable toothed elements operable upon such movement of said first-named contacts to effect such movement of said second contacts.

70 In testimony whereof I have hereunto subscribed my name at Zurich, Switzerland, this 30 day of March, A. D. 1927.
